Primary Examiner — Mehri F Bajoul(74) *Attorney, Agent, or Firm* — Justin Lampel(57) **CLAIM**

The ornamental design for a roundnet frame, as shown and described.

DESCRIPTION

FIG. 1 is a perspective view of a roundnet frame showing my new design;

FIG. 2 is a side elevational view thereof;

FIG. 3 is another side elevational view thereof;

FIG. 4 is a front elevational view thereof;

FIG. 5 is a back elevational view thereof;

FIG. 6 is a top plan view thereof;

FIG. 7 is a bottom plan view thereof;

FIG. 8 is a cross-sectional view thereof, taken along the line 8-8 in FIG. 6; and,

FIG. 9 is another cross-sectional view thereof; taken along the line 9-9.

The dash-dot lines in FIGS. 8 and 9 illustrate the bounds of the cross-cut sections of the roundnet frame and form no part of the claimed design.
